UNITED STATES PATENT OFFICE.

RICHMOND PARSONS, OF PHILADELPHIA, PENNSYLVANIA.

INTERLOCKING DEVICE FOR TRUNKS.

1,209,016.

Specification of Letters Patent. Patented Dec. 19, 1916.

Application filed September 1, 1916. Serial No. 118,118.

To all whom it may concern:

Be it known that I, RICHMOND PARSONS, a citizen of the United States, residing at Philadelphia, in the county of Philadelphia and State of Pennsylvania, have invented certain new and useful Improvements in Interlocking Devices for Trunks, of which the following is a specification.

My invention consists of improvements in interlocking devices for trunks, and is particularly serviceable for use on wardrobe trunks.

One of the objects of my invention is to provide a device which will be operative to 15 securely lock trunks and when in its locked position, will serve to reinforce the trunk.

Another object of my invention is to provide locking means which will automatically unlock when another lock is opened by a 20 key or other selective means, said locking means being simultaneously locked when said other lock is closed.

A still further object is to make my improved interlocking device of a durable and 25 simple construction which can be manufactured and applied at a comparatively low cost.

These objects, and other advantageous ends which will be described hereinafter, I 30 attain in the following manner, reference being had to the accompanying drawings in which—

Figure 1 is a perspective view of a wardrobe trunk having my improved interlocking device thereon. Fig. 2 is a fragmentary elevation showing the interior of a trunk having my improved interlocking device thereon, said view showing the manner in 35 which the two sections of the trunk are secured together by my invention. Fig. 3 is a section on the line *a—a* of Fig. 2, and Fig. 4 is an inverted sectional plan view on the line *b—b* of Fig. 2.

Referring to the drawings, 1 represents a 40 wardrobe trunk having two sections 2 and 3 which separate on the parting line 4. A lock 5 is secured to the outer face of the trunk and bridges or extends across the parting 4. The section 6 of the lock is rigidly secured to the section 3 of the trunk, and the section 7 of said lock is hinged at 8 to the section 6.

The section 7 of the lock is provided with a plug portion 9 which enters a hole 10 in a lock casing 11, the latter having a sleeve 12 which fits an opening or hole 13 which ex-

tends entirely through the section 2 of the trunk.

The sleeve 12 is securely mounted on the section 2 of the trunk, and its inner end 60 forms an abutment for bolts 14 which are retracted by the insertion and movement of a key within the lock to permit the opening of said lock.

On the inner surface of the trunk section 65 2, I secure a plurality of substantially U-shaped members 15 which have ears 16 riveted or otherwise fastened to the section 2. These members form a slide-way for a longitudinally extending bar 17 which has 70 thereon pins 18 provided with heads 19. These pins 18 extend through slots 20 on locking arms 21 pivoted at 22 to bearing plates 23 on the trunk section 2. These arms 20 have their opposite ends 24 provided with a hook designed to enter loops 75 25 made of strap metal or other suitable material. These loops 25 are secured by rivets or other means to the inner surface of the trunk section 3, and in the present instance extend across the parting 4, so that when the hooked ends 24 of the arms engage the loops 25, they act to securely hold the trunk sections 2 and 3 together.

A plate 26 is secured to the inner surface 85 of the trunk section 2 and in substantial alinement with the bar 17. A hinge 27, consisting of two plates 28 and 29, is positioned between the bar 17 and plate 26. The plates 28 and 29 are hinged together at 30, the opposite ends of the plates 28 and 29 being 90 respectively hinged to the plate 26 and to the bar 17 as shown at 31 and 32.

A coiled tension spring 33 has its opposite ends attached to pins 34 on each of the 95 plates 28 and 29. The hinged portion 30 of the plates 28 and 29 is so located that when the lock 5 is closed, the plug portion 9 thereof will serve to keep the plates 28 and 29 and the bar 17 in the position illustrated in 100 full lines in the drawing with the arms 21 in locking engagement with the loops 25. When the hinge 30 is held in this position, the spring 33 is under tension, and serves to keep the hinge 30 in engagement with the 105 plug portion 9.

When the lock 5 is opened, the spring 33 will then act to force the hinge portion 30 into the hole previously occupied by the plug portion 9, and in so doing will cause 110 the bar 17 to be moved longitudinally and thereby move the hooked ends 24 of the

arms 21 out of the loops 25, and thereby permit the trunk sections 2 and 3 to be opened. This position assumed by the hinge portion 30 and the bar 17 is shown in 5 dot-and-dash lines in Fig. 3.

To again lock the trunk, it is only necessary to push the plug portion 9 of the lock 5 into the hole provided for it, and during this movement, the plug engages the hinge 10 portion 30 and pushes it into the full line position illustrated to again partially straighten out the hinge and stretch the spring 33. This latter movement serves to move the bar 17 to again bring the hooked 15 ends 24 of the arms 21 into the loops 25.

It will thus be seen that the opening of the lock 5 permits the automatic unlocking movement of the interior locking means, and that the closing of the lock 5 also effects the 20 locking of said interior locking means.

It will thus be understood that by opening the lock 5, the spring 33 will act to automatically unlock all of the arms 21 from their respective loops 25.

25 In the drawings, I have illustrated only two arms 21, but it will be understood that any number may be used if desired.

While I have described my invention as taking a particular form, it will be understood that the various parts of my invention may be changed without departing from the spirit thereof, and hence I do not limit myself to the precise construction set forth, but consider that I am at liberty to make 35 such changes and alterations as fairly come within the scope of the appended claims.

Having thus described my invention, what I claim as new and desire to secure by Letters Patent is:

40 1. The combination of a trunk, a lock thereon, additional locking means for the trunk including a hinged joint designed to abut said first lock when the latter is in its closed position, and automatic means operative to bend said hinged joint and thereby move said additional means into an unlocked position when said first lock is opened, substantially as described.

2. The combination of a trunk having a 45 hole therein, a lock on the outside of said trunk having a portion exposed to the interior of said trunk through the medium of said hole, additional locking means slidably mounted on the interior of said trunk, a 55 hinged joint connected to said locking means and designed to abut said interior exposed portion of said lock, means secured to the interior of said trunk, and connected to said hinged joint, and automatic means operative to bend said hinged joint and thereby move said additional locking means into 60 an inoperative position when said first lock is opened, substantially as described.

3. The combination of a trunk having a hole therein, a lock on the outside of said 65 trunk having a portion extending into said hole, additional locking means on the interior of said trunk and including a hinged joint, for engagement with a portion of the lock when the latter is in its closed position, 70 and a spring for moving said joint when permitted to do so by the opening movement of the lock, whereby said additional means is unlocked, substantially as described.

4. The combination of a trunk having a 75 hole therein and made in two sections, a lock on the outer face of the trunk and having a portion exposed to the interior of the trunk through the medium of said hole, additional locking means on the interior of 80 said trunk including a slideable bar, a fixed member secured to the interior, two members hinged to each other and respectively hinged to the fixed member and to the slideable bar, a spring connecting said hinged 85 members and operative, when the first lock is moved to an open position, to move the members on their hinge and thereby effect longitudinal movement of said bar, said bar having locking means connected therewith 90 which is released by said movement of the bar, substantially as described.

5. The combination of a trunk made in two sections, one of said sections having a hole therein, a hinged lock having a portion secured to one of said sections and having another portion designed to cover the hole in the other of said sections, a bar slidably movable within said trunk, a plate fixed within said trunk and in substantial 100 alignment with said bar, two plates hinged together and to the first-mentioned plate and to the bar, a tension spring connecting said second-mentioned plates, arms pivoted to the interior of one of said trunk sections, 105 loops secured to the interior of the other of said sections, means operatively connecting the bar with said arms to move their hooked ends into and out of engagement with said loops, said outer lock when in its 110 closed position acting to prevent movement of said plates by the spring and thereby hold the arms in their locked positions, said spring, when the lock is moved into an open position, acting to move said second-mentioned plates into the space previously occupied by said first lock when in its closed position, substantially as described.

115 In testimony whereof I have signed my name to this specification in the presence of two subscribing witnesses.

RICHMOND PARSONS.
